CLAIM

The ornamental design for a combined dispenser and lid, as shown and described.

DESCRIPTION

FIG. 1 is an exploded top front and right side perspective view of a combined dispenser and lid showing my new design;

FIG. 2 is a side elevational view of a combined dispenser and lid with the lid in the closed position, the undisclosed opposite side being a mirror image;

FIG. 3 is a top plan view of FIG. 2; and,

FIG. 4 is a bottom plan view of FIG. 2.

FIG.1.

FIG. 3.

FIG. 2.

FIG. 4.
